(57) **CLAIM**

I claim the ornamental design for a knife with a gut hook tip, as shown and described.

DESCRIPTION

FIG. 1 is a right-side elevation view of a knife with a gut hook tip showing my new design;

FIG. 2 is a left-side elevation view thereof; and,

FIG. 3 is a rear, right and top perspective thereof.

The broken lines depict environmental structure and are included for the purpose of illustrating only and form no part of the claimed design.
